(57) **CLAIM**

The ornamental design for a hook design, as shown and described.

DESCRIPTION

FIG. 1 is a perspective view of a hook design showing the new design;

FIG. 2 is a front view thereof;

FIG. 3 is a top view thereof;

FIG. 4 is a back view thereof;

FIG. 5 is a left side view thereof, the right side view thereof being a mirror image of the left side view shown; and, FIG. 6 is a bottom view thereof.

The surface shading illustrated in the drawings is provided merely to highlight the contour of design; it is not intended to be illustrative of texture or gloss.
